FOUNTAIN COMB AND BRUSH

Charles M. Hickey, New York, N. Y.

Application April 11, 1940, Serial No. 329,023

5 Claims. (Cl. 132—13)

This invention relates to fountain combs, brushes or the like and refers more particularly to means for forcibly feeding a liquid to the teeth or bristles thereof, and the same is an improvement on my co-pending application, Serial No. 284,743.

The invention comprehends improved pump means for forcibly feeding a liquid to the teeth of a comb or to the bristles of a brush or the like and which pump means is so constructed and arranged as to prevent leakage of the liquid where the pump manipulating means protrudes through the comb or brush.

The invention further embodies in a device 15 of the indicated character, a reservoir for holding a supply of liquid, a discharge chamber having ports through which the liquid is discharged, a piston mounted for longitudinal reciprocatory movement within the device for pumping the liquid from the reservoir and forcing the same into the discharge chamber and through the discharge ports, means protruding through the wall of the device for manipulating the piston, and means engaging about the piston at spaced 20 points thereon to provide a seal for preventing leakage of the liquid about the manipulating means.

The invention further embodies a pump cylinder communicating with the reservoir, a piston having a passageway extending longitudinally therethrough and mounted for longitudinal reciprocatory movement with its forward end disposed in said pump cylinder, valves normally closing the inlets to said pump cylinder and passageway, a guide for said piston and flexible resilient means sealed about said piston at spaced points thereof and at the opposite ends of said guide for preventing leakage of the liquid from the reservoir and discharge chamber through the guide openings for the pump manipulating elements.

With the foregoing and other objects in view, reference is now made to the following specification and accompanying drawing in which there is illustrated the preferred embodiment of the invention.

In the drawing:

Fig. 1 is a longitudinal vertical section of a comb constructed in accordance with the invention and illustrating the pumping means in side elevation with the piston at one end of its stroke.

Fig. 2 is an enlarged fragmentary horizontal sectional view taken on the line 2—2 of Fig. 1, illustrating the piston at the opposite end of its stroke.

Fig. 3 is an enlarged transverse sectional view taken approximately on the line 3—3 of Fig. 2.

Fig. 4 is a similar view taken on line 4—4 of Fig. 2.

Fig. 5 is a fragmentary sectional view similar 5 to Fig. 1 and illustrating the comb provided with absorptive means for retaining the liquid discharged through the ports.

Fig. 6 is a fragmentary longitudinal sectional view taken approximately on the line 6—6 of 10 Fig. 5.

Fig. 7 is a transverse sectional view taken approximately on the line 7—7 of Fig. 5.

Fig. 8 is a side view of a brush constructed in accordance with the invention. 15

Referring to the drawing by characters of reference, the comb illustrated in Figs. 1 to 7 inclusive, includes an elongated hollow body 10 provided with a row of teeth 11 extending from one end thereof to approximately the middle 20 portion thereof and which comb portion of the body is of reduced width and of substantially rectangular shape in cross section, while the forward portion 12 thereof is enlarged and of generally ovate form in cross section to serve 25 as a handle.

The body 10 is provided with a transverse web extending from the end wall 14 to approximately the middle of the handle portion 12 and which web includes a portion 15 coextensive with the 30 row of teeth 11 and forming with the bottom wall of the comb portion of the body a liquid passage 16 having longitudinal spaced ports 17 opening between adjacent pairs of comb teeth and defining a liquid outlet manifold. The said 35 web also includes a forwardly extending arcuate portion 18 which forms with the bottom wall of the handle portion 12 adjacent the row of teeth 11, a discharge chamber 19 communicating with the outlet passage 16. The said web further includes a forward arcuate portion 20 providing with the bottom wall of the handle portion 12 a bore 21 which communicates with and is disposed in alignment with the discharge chamber 19. The body 10 is also provided with a 45 transverse web 22 which is spaced forwardly of the web portion 20 and forms with the bottom wall of the body of the comb a bore 23 which is open at its opposite ends and aligns with the bore 21. 50

Fitted within the bore 23 and coextensive therewith is a tubular member or pump cylinder 24 having a valve casing 25 secured within its forward end and which valve casing is provided with an axial bore 26 having a reduced inlet 27 55

and a valve seat 28 for a ball valve element 29. The valve element 29 is normally retained in closed position on the seat 28 by a coiled expansion spring 30 positioned in the bore 26 between the ball valve element and the inturned outer end 31 of the casing 25.

The upper portion of the body 10 of the comb forms a reservoir 33 for holding a supply of liquid and in order to provide means for forcibly feeding the liquid to the teeth of the comb, a piston, indicated generally by the reference character 34, is provided which includes a piston head 35 mounted for longitudinal reciprocatory movement in the pump cylinder 24 and which is secured to the forward end of a tubular stem 36 extending axially through the bore 21 and protruding into the discharge chamber 19. The piston head 35 is provided with an axial bore 37 which aligns with the bore 36' of the stem 36 and which bores from a longitudinal passageway through the piston, the head 35 thereof being formed with a reduced inlet 38 and a seat 39 for a ball valve element 40 which is normally urged to close the inlet 38 and said passageway by means of a coiled expansion spring 41 positioned between the ball valve 40 and the inner end of the tubular stem 36.

The piston 34 is tensioned by a coiled expansion spring 42 which normally urges the piston towards the forward end of its stroke. The spring 42 is disposed within a tubular element 43 in surrounding relation to the stem 36 between the inturned outer end 44 of the tubular element 43 and a collar 45 secured to the stem 36 and slidably fitted within the tubular element 43. The tubular element 43 is secured within the bore 21 and provides a hollow cylindrical or tubular guide for the piston 34. The collar 45 is provided with a pair of outwardly projecting manipulating studs 46 which protrude through aligned longitudinally extending slots 47 and 48 in the tubular element or guide 43 and the side wall of the body 10 either or both of which studs may be used to actuate the piston.

In order to prevent leakage of the liquid from the reservoir 33 and the discharge chamber 19 through the slots 47 and 48, a pair of oppositely flared flexible sleeves 49 and 50 are provided which have their adjacent enlarged ends secured as at 51 and 52 respectively in surrounding sealing relation on the opposite ends of the tubular element or guide 43 and between the same and the web portion 20 and the outer wall of the comb defining the bore 21. The outer reduced ends of the sleeves 49 and 50 are secured as at 53 and 54 in surrounding sealing relation upon the stem 36 at the outer end thereof and at the rear of the piston head 35 respectively.

The forward end of the handle portion 12 is provided with a threaded filling opening 56 which is closed by a screw plug 57 having an air inlet opening 58 extending therethrough for admitting air to the reservoir 33 as the liquid is pumped therefrom. The air inlet 58 is closed by a conical valve 59 normally urged into closing relation with the valve seat 60 by means of a coiled expansion spring 61 positioned between the inner end of the valve 59 and the inturned inner end 62 of the screw plug 57. The valve 59 is provided with a push rod 63 protruding through the outer end of the inlet 58 for manually opening the valve for admitting air to the reservoir 33.

When the liquid fed by the pump to the row of teeth 11 is of a nature that the same will stain, the row of teeth 11 at the base thereof is provided

with an aligned opening 65 in which is positioned an elongated strip 66 of felt arranged adjacent to the discharge ports 17 for receiving and absorbing the liquid as the same is discharged therefrom. The strip 66 is secured in position by means of a wire bail 67 engaging on opposite sides of the felt strip and secured at its inner end in a recess 68 and having its opposite free ends secured in a plug 69 threadedly engaging the opening 70 at the rear of the comb.

In operation the liquid is pumped from the reservoir 33 to the comb teeth through the ports 17 by actuating the pump through the medium of the manipulating heads to reciprocate the piston 34 longitudinally of the bore 21. As the piston is moved to the left, the ball valve 40 is unseated so as to draw the liquid through the inlet 38 into the pump chamber 23 during which movement the ball valve 40 is seated to close the inlet 38 and the passageway through the stem 36. The liquid drawn into the pump cylinder 23 is then forced through the passageway in the stem 36 by movement of the piston 34 in the opposite direction or to the right. This completes a cycle of movement of the piston where relatively few actuations or reciprocations of the piston are sufficient to supply the required quantity of the liquid to the teeth. When the piston is moved to the left, as illustrated in Fig. 1, the flexible sleeve 49 is longitudinally contracted as illustrated in said figure and the flexible sleeve 50 is longitudinally extended, as illustrated thereon. When the piston is moved in the opposite direction, the flexible sleeve 49 will be longitudinally extended and the flexible sleeve 50 will be longitudinally contracted as illustrated in Fig. 2.

The invention, as illustrated in Figs. 1 to 7 inclusive, is shown in its application to a comb but it is to be understood that the invention is applicable to brushes such as hair brushes, tooth brushes and the like as illustrated in Fig. 8. In this form of the invention, the body 75 is of hollow construction and is similar to the body 10 illustrated in Figs. 1 to 7 inclusive, and includes a pump mechanism 76 similar in all respects to the pump mechanism illustrated in Fig. 1 and as described in connection with Figs. 1 to 7 inclusive. Leading from the discharge chamber 17 is a liquid outlet passage 78 similar to the passageway 16 and from which outlet passage 78 longitudinally spaced discharge ports 79 are provided which open to the bristles 80 and which bristles form the applicator elements for applying liquid to the hair or teeth, similarly to the teeth 11 in the comb illustrated in Figs. 1 to 7 inclusive.

What is claimed is:

1. In a device of the character described, a hollow body, applicator elements projecting outwardly along one portion thereof, the interior of said body forming a reservoir for holding a supply of liquid, means within said body defining a liquid discharge chamber and a manifold outlet passage to the applicator elements, a pump cylinder having an inlet communicating with said reservoir, a hollow cylindrical guide disposed intermediate the discharge chamber and said pump cylinder, a reciprocatory piston having a longitudinal passageway therethrough and disposed intermediate its ends within said cylindrical guide with its forward end projecting into said pump cylinder and its opposite end communicating with said discharge chamber, valves normally closing the inlets to said pump cylinder and said passageway through the piston respec-

tively, said cylindrical guide and said body having longitudinally extending registering openings through the walls thereof, a manipulating means connected to said piston and protruding through said openings for manually actuating the piston, and flexible sleeves sealed about said piston at spaced points thereon and at the opposite ends of said guide for preventing leakage of the liquid through the said longitudinal opening in the 10 wall of the body.

2. In a device of the class described, a hollow body, applicator elements projecting outwardly along one portion thereof, the interior of said body forming a reservoir for holding a supply of liquid and having ports open to the applicator elements, a reciprocatory piston for forcibly feeding the liquid from the reservoir through the said ports to the applicator elements, a tubular guide surrounding said piston intermediate its ends, said guide and said body having longitudinally extending registering openings through the walls thereof, a manipulating means connected with said piston to move therewith and protruding through said openings for manually actuating the piston, and flexible sleeves sealed about said piston at spaced points thereon and at the opposite ends of said guide for preventing leakage of the liquid through said longitudinal opening in the wall of the body.

3. In a fountain comb, a reciprocatory piston for pumping a liquid to the teeth of the comb, a tubular guide within said comb surrounding said piston intermediate its ends, a manipulating means connected with said piston to move therewith and protruding through a wall of the comb, and flexible means sealed about said piston at spaced points thereon and at the opposite ends of said guide for preventing leakage of the liquid

uid through the wall of the comb about the manipulating means.

4. In a fountain comb, a hollow body, a row of teeth projecting outwardly along one portion thereof, the interior of said body forming a reservoir for holding a supply of liquid, means within said comb defining a liquid discharge chamber and an outlet passage having ports opening to the teeth of said row, a reciprocatory piston for pumping a liquid from said reservoir to the discharge chamber and through the said ports, absorptive means carried by the teeth of said row and disposed adjacent to said ports for receiving and absorbing the liquid discharged therethrough, a tubular guide within said comb surrounding said piston intermediate its ends, a manipulating means connected with said piston to move therewith and protruding through a wall of the comb, and flexible sleeves sealed about said piston at spaced points thereon and at the opposite ends of said guide for preventing leakage of the liquid through the wall of the comb about the manipulating means.

5. In a fountain comb, a reciprocatory piston for pumping a liquid to the teeth of the comb, a tubular guide within said comb surrounding said piston intermediate its ends, a manipulating means connected with said piston to move therewith and protruding through the wall of the comb, and oppositely flared flexible sleeves having their enlarged ends secured respectively in surrounding sealing relation on the opposite ends of the tubular guide and their reduced ends secured respectively in surrounding sealing relation upon the piston at the free end thereof and at the rear of the piston head for preventing leakage of the liquid through the wall of the comb about the manipulating means.
